UNITED STATES PATENT OFFICE.

WILBER A. K. CAMPBELL, OF LITTLE YORK, ILLINOIS.

DESIGN FOR A KITCHEN-CABINET.

SPECIFICATION forming part of Design No. 34,509, dated May 14, 1901.

Application filed April 18, 1901. Serial No. 56,522. Term of patent 14 years.

To all whom it may concern:

Be it known that I, WILBER A. K. CAMPBELL, a citizen of the United States, residing at Little York, in the county of Warren and State of Illinois, have invented and produced a certain new and original Design for Kitchen-Cabinets; and I do declare the following to be a full, clear, and exact description of the invention, such as will enable others skilled in the art to which it appertains to make and use the same.

The invention relates to a new and original design for a kitchen-cabinet; and it consists of a design of the shape or configuration shown in the accompanying drawings, in which—

Figure 1 is a front view, and Fig. 2 is a top plan view, of my design.

The leading features of the design consist of a base 1, a cylindrical hopper 2, having a removable cover 3, and a drawer 4, and arranged in juxtaposition to a polygonal upright easing 5, having a vertical row of drawers 6 and a pyramidal cap-piece 7.

What I claim is—

The design for a kitchen-cabinet as herein shown and described.

In testimony whereof I have hereunto set my hand in presence of two subscribing witnesses.

WILBER A. K. CAMPBELL.
